Metal Products, Incorporated, Aurora, Ill., a corporation of Illinois

Application October 21, 1937, Serial No. 72,356

Term of patent 7 years

To all whom it may concern:

Be it known that I, John B. O'Connor, a citizen of the United States, residing at Aurora, in the county of Kane and State of Illinois, have invented a new, original, and ornamental Design for a Chair of which the following is a specification, reference being had to the accompanying drawing, forming part thereof.

The figure is a perspective view of a chair, embodying my new design.

I claim:

The ornamental design for a chair, substantially as shown.

JOHN B. O'CONNOR.
